UNITED STATES PATENT OFFICE.

WILLIAM HARRIS, OF PATERSON, NEW JERSEY.

LET-OFF MEANS FOR LOOMS.

Application filed December 14, 1923, Serial No. 680,602. Renewed January 26, 1925.

To all whom it may concern:

Be it known that I, WILLIAM HARRIS, a citizen of the United States, residing at Paterson, in the county of Passaic and State 5 of New Jersey, have invented certain new and useful Improvements in Let-Off Means for Looms, of which the following is a specification.

In an application for Letters Patent of 10 the United States executed by me on even date herewith, Serial No. 680,601, I have set forth a let-off mechanism for looms which in one form thereof included a flexible attenuated tensioning connection 15 between a part of the rotary warp-supply means of a loom and a rotary member confined to rotate in synchrony with the means for exerting a pull on the warp to cause it to unwind from the element of the warp- 20 supply means on which the warp is wound, said connection being in permanent tractive engagement with said part and extending therefrom relatively reversely to the direction in which the warp extends from said 25 element and being also in tractive engagement with said member and arranged to be paid out thereby when the second-named means is exerting a pull on the warp; in that case the tractive engagement was ob- 30 tained in each instance by forming the connection with ends and coiling the ends around said part and member, one end portion thereof winding up on said part and the other unwinding from said member as 35 the warp is pulled from the supply means. In the present construction I form the connection endless, which has the advantage that the necessity for rehabilitating the connection from time to time because it becomes 40 wound up on said part and unwound from said member is avoided. In this construction I further provide for different diameters or steps as to either said part or the part of said member with which the tensioning connection is in tractive engagement 45 so that the connection may be first engaged with one of these steps and, as the weaving proceeds, then with the other, all with an object in view which will hereinafter appear. As to this feature I remark that it 50 is not material to the invention whether the tensioning is endless or even flexible.

The drawing shows my invention in side elevation in operative association with a 55 loom.

In a frame or other support *a* are the

breast-beam *b* and a roller *c* over which the warp *A* (having interwoven with it the weft or filling and so as to its forward portion being a part of the fabric *B*) is extended as usual. At the front of the loom is arranged a take-up mechanism of any usual form, the same being here represented by a sand-roller *d* and a cloth-beam *e* on which to wind up the part of the warp with which the weft or filling has been incorporated to form the fabric, the latter being maintained in a bend around the sand-roller by two other rollers *f*, as usual. The sand-roller is kept from backward rotation by 60 any suitable means, here shown as a holding pawl *d'* engaging a ratchet *d''* fixed to rotate with the sand-roller. The sand-roller is kept from backward rotation by 65 any suitable means, here shown as a holding pawl *d'* engaging a ratchet *d''* fixed to rotate with the sand-roller. It is not material to the present invention in what manner or by what means the sand-roller and beam *e* 70 are rotated to advance and wind up the fabric.

At the rear of the loom is journaled the warp-beam *g*. It has on the end of one of its gudgeons *h* and in the present example 80 constituting a separately formed part a wheel *i* in the form of a sprocket wheel, which in the present example is arranged outward of the loom frame.

On the sand-roller shaft is another such 85 wheel formed stepped as at *k'-k''* and here of the sprocket type.

The aforementioned flexible attenuated tensioning connection is here shown as comprising an endless sprocket chain *l*, which 90 is in tractive engagement with the wheel *i* and with one of the steps of wheel *k'-k''* and which extends over two guides (here pulleys *t'-t'* on frame *a*), and tension means engaged with a bight or bend *l''* in the 95 chain depending between the two guides, said means here including a weight-carrier *m* carrying one or more weights *n* and having a pulley *o* engaged in the bend. The 100 said connection extends from wheel *i* relatively reversely to the direction in which the warp *A* is wound on the beam *g* (a good tractive engagement between the same and the wheel being maintained by idler wheels *p*) and it extends from wheel *k'-k''* relatively 105 reversely to the direction in which the warp is advanced by the sand-roller; in other words, the relation of the connection to the two wheels *i* and *k'-k''* is such that when the warp is pulled forward, as by the sand-roller, and so is unwound from the beam *g*, the chain travels in the direction 110

of the arrow shown, being paid out at $k'-k''$ as it is taken up at i , the weight all the while keeping the chain taut and thus acting on both ends of the warp to maintain 5 the desired tension on the warp.

The improved let-off mechanism is used as follows: The warp is advanced by the sand-roller, as usual, at a constant speed. But the wound mass of warp on the beam g 10 diminishes in diameter, so that the rotation of the beam is constantly accelerated. Therefore, any initial slack in the chain represented by bight or bend l'' will in time be taken up because the speed of wheel i 15 is accelerating while that of $k'-k''$ is constant. At the outset, the chain is made to engage the smaller step k' of the wheel $k'-k''$, but when the slack at l' is about 20 to be expended the weaver shifts the chain to the next larger step so that for a time at least the rate of advance of the chain at $k'-k''$ will be increased and so there will now ensue an augmentation of slack. There may of course be any number of steps 25 to wheel $k'-k''$, depending upon the length of warp usually used in the loom.

The chain being endless in the present example it remains interminably operative so long, at least, as it is shifted from one step 30 to another at $k'-k''$ when necessary; and when the slack therein at l'' is taken up slack accumulates at l^2 , the latter slack being expended when the slack at l^2 is forming.

It is obvious that it is not material 35 whether the stepped formation is applied to the let-off mechanism (as at i) or to the take-up mechanism (as at $k'-k''$, the actual condition shown and described).

By the term "permanent tractive engagement" as herein used I mean a tractive engagement not permitting slippage; this is 40 obtained in the example described and shown

by toothed sprocket wheels and a chain (j) engaged therewith.

Having thus fully described my invention, 45 what I claim as new and desire to secure by Letters Patent is:—

1. In a loom, the combination of a support, rotary means to supply the warp journaled in said support and including a rotary 50 element on which the warp is wound, means to exert a pull on the warp and thereby unwind it from said element, causing rotation of the first means, a rotary paying-out means confined to rotate in synchrony with the 55 second-named means, and an endless flexible tensioning connection in permanent tractive engagement with a part of the first means and a part of the paying-out means and imparting force to rotate the former part relatively 60 contrary to the pull of the warp and to rotate the latter part in relatively the same direction as the warp is pulled.

2. In a loom, the combination of a support, rotary means to supply the warp journaled in said support and including a rotary 65 element on which the warp is wound, means to exert a pull on the warp and thereby unwind it from said element, causing rotation of the first means, a rotary paying-out means 70 confined to rotate in synchrony with the second-named means, and a tensioning connection in permanent tractive engagement with a part of the first means and a part of the paying-out means and imparting force to 75 rotate the former part relatively contrary to the pull of the warp and to rotate the latter part in relatively the same direction as the warp is pulled, and one of said parts including steps with either of which said connection may be tractively engaged at will. 80

In testimony whereof I affix my signature.

WILLIAM HARRIS.
